UNITED STATES PATENT OFFICE.

SPARKMAN R. SCREVEN, OF PHILADELPHIA, PENNSYLVANIA.

DENTAL-ENGINE HAND-PIECE.

SPECIFICATION forming part of Letters Patent No. 288,499, dated November 13, 1883.

Application filed December 22, 1882. (No model.)

To all whom it may concern:

Be it known that I, SPARKMAN R. SCREVEN, a citizen of the United States, residing in the city and county of Philadelphia, State of Pennsylvania, have invented a new and useful Improvement in Dental-Engine Instruments; which improvement is fully set forth in the following specification and accompanying drawings, in which—

10. Figure 1 is a side elevation of a hand-piece, partly sectional, having my invention applied to it. Fig. 2 is an enlarged view of an instrument embodying my invention. Fig. 3 is a partial longitudinal section and side elevation of another instrument embodying my invention. Fig. 4 is a partial side elevation and longitudinal section of another instrument embodying my invention. Fig. 5 is a section in line $x x$, Fig. 3.

20. Similar letters of reference indicate corresponding parts in the several figures.

My invention consists in forming a dental-engine instrument of two parts, which are detachably connected by a tongue and groove, the tongue being in one piece with one of said parts, and flush with the exterior thereof when they are fastened together. The hand-piece controls the interlocking devices of the two parts, as will be hereinafter set forth.

30. Referring to the drawings, A represents a hand-piece of a dental engine, and B an instrument adapted to be fitted and secured thereto. The instrument is formed of two parts, a b , the part a being the instrument proper, and the part b being a socket which receives the butt-end of the part a and is locked thereto, said socket being adapted to be fitted within the hand-piece and connected therein by any suitable means, it being seen

40. that when the engine is operated the two parts a b rotate as one similar to dental-engine instruments in use. When the part a is broken, it is removed and replaced by a fresh piece, said part a being the only loss, as the part b or socket remains intact, ready for application of the fresh piece or part. Furthermore, although numerous instruments are employed by a dentist, and often many changes are required in an operation, only a single socket

50. part is necessary for the number of instruments, thus effecting a great saving in the cost of instruments of the class. The same instrument may be used with any hand-piece, pro-

vided the socket part is adapted to be fitted to said piece.

55. In the wall of the socket part b , near the front end thereof, is formed a longitudinally-extending recess, in which is fitted a spring-tongue, C, whose inner face has a nose, c , and in the butt-end of the part a is a groove or notch, d , so disposed that it is adapted to receive the nose of the tongue. The tongue C is adapted to yield, but has no hinge, being rigidly connected with the part b as one or integral. Its exterior coincides or is flush with the curvature of the remainder of the surface of the part b , so that when the tongue is closed the part b and tongue C present an unbroken surface, which is encircled by the cylindrical wall of the contiguous part of the hand-piece. 65. Now, when the socket part is inserted into the hand-piece, the sleeve of the latter encircles the socket part, and consequently the tongue B, and forces the latter inwardly, thus inserting the nose c into the groove or notch d , and locking the two parts a b as one, the sleeve of the hand-piece controlling said tongue C, and causing a firm connection of the instrument with said hand-piece. In order to remove the instrument, the hand-piece is operated to disengage or unlock the socket part from said piece, after which both parts a b may be withdrawn as one from the hand-piece. The part 70. a is then rotated, whereby the portion of said part on the right or left of the groove or notch d raises the tongue C clear of said groove or notch, so that the part a may be drawn out from the socket b .

75. I am aware that it is not new to make a dental-engine implement of two detachable parts, 90. these parts being connected by a spring-catch, and one part fitting into the other.

Having thus described my invention, what I claim as new, and desire to secure by Letters Patent, is—

95. A dental-engine instrument formed of two parts—viz., a socket part and the instrument part proper—said parts having a tongue and groove, respectively, said tongue being in one piece with its part and flush with the exterior thereof, substantially as and for the purpose set forth.

SPARKMAN R. SCREVEN.
